UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

LAMP CLUSTER AND SWITCH.

SPECIFICATION forming part of Letters Patent No. 767,681, dated August 16, 1904.

Application filed May 7, 1903. Renewed May 2, 1904. Serial No. 206,038. (No model.)

To all whom it may concern:

Be it known that I, REUBEN B. BENJAMIN, a citizen of the United States, residing at Chicago, in the county of Cook and State of Illinois, have invented a certain new and useful Improvement in Lamp Clusters and Switches, of which the following is a full, clear, concise, and exact description, reference being had to the accompanying drawings, forming a part 10 of this specification.

My invention relates to improvements in electric-lamp clusters.

It has for its object to combine with a plurality of lamp-holding devices having associated contacts a switch arranged as hereinafter set forth for controlling the circuit of the lamps.

A further object of the invention is to produce a lamp-cluster having a switch associated therewith for controlling the circuits of the lamps which will be cheap to manufacture, simple in construction, and neat in appearance.

In accordance with my invention in the preferred form thereof I provide a main supporting-base adapted to be mounted in position in any of the customary ways, a supplemental base mounted in front of and parallel to said supporting-base, lamp-receivers and associated contacts mounted in any suitable manner between said supporting and supplemental bases, an inclosing casing having an opening opposite each lamp-receiver, and the elements of a suitable switch carried upon the front of said supplemental base. In this manner all of the live parts of the socket are inclosed between the two bases and the casing, while the supplemental base effectively insulates the switch-contacts from the casing and the circuit-conductors of opposite polarity. The switch parts thus occupy a centrally-disposed position, and the handle thereof is readily accessible in operating the switch.

The accompanying drawings show the preferred embodiment of my invention, and therein the several views are as follows:

Figure 1 is a sectional elevation taken on

the line $\alpha\alpha$ of Fig. 2. Fig. 2 is a plan view of my improved device. Fig. 3 is a plan view of said device with the switch and casing 50 thereof removed to show more particularly the interior arrangement of the cluster. Fig. 4 is an interior view of the switch mechanism, showing the switch open. Fig. 5 is a similar view showing the switch closed, and Fig. 6 is 55 a view showing a modification of my invention.

Referring now to the drawings, therein is shown a main supporting-base of suitable material, such as porcelain 1, adapted to be attached to a suitable support. The base has a 60 central raised portion 2, provided with an opening 3. Upon said base is mounted a spun or truncated plate 4, which has inclined side walls and a preferably flat bottom. At one side of the bottom is arranged an opening 5, and the side walls of said truncated plate are provided with a plurality of openings in which are arranged lamp-receiving shells 6. Each lamp-receiving shell preferably has an outwardly-flared flange, which 65 bears against the inner portion of the side walls and which is secured to said plate by solder or other means for securing or fastening the lamp-receiving shell in position on the truncated contact-plate.

Upon the central raised portion of the base is arranged a plurality of center contacts 8, one being provided opposite each lamp-receiving shell. The several center contacts are preferably electrically connected by a 80 metallic strip or plate 10, which is secured to the base by screws or other means and which holds said center contacts in position. This plate is provided with a binding-screw 11 for connecting therewith one of the supply-wires, 85 which may be brought in through the opening 3 in the base. The bottom of the truncated plate has secured thereon, preferably by screws, a switch-base 12. This base carries suitable stationary contacts 13, which are 90 adapted to be bridged by a movable contact 14. The several contacts of the switch mounted upon the base 12 are preferably inclosed by a casing 15, and a stem 16, having a knob

17, is provided for operating said switch. The switch here shown is of the snap type, the construction of which is well understood; but of course any desirable form of switch may 5 be employed. The base for the switch is provided with an opening 18, and a suitable binding-post 19 is provided for connecting one of the supply-wires to one of the stationary contacts of the switch. Upon the bottom of the 10 truncated plate is preferably secured a pin 20, which passes through an aperture made to receive the same in the base and which is connected with a binding-post 21 of the other stationary contact.

15 A suitable casing 22 is provided for the lamp-receiving shells. This casing is provided with an aperture opposite each of the lamp-receiving shells to permit the insertion of the lamps into said shells, and said casing 20 is also provided with a central opening to receive the base of the switch. This casing is insulated from the live parts of the device by the base of the cluster and the base of the switch, and bushings 23 are inserted between 25 the lamp-receiving shells and the casing to insulate said shells from said casing. Said bushings are preferably screw-threaded upon the lamp-receiving shells and support the casing for the cluster in position.

30 In Fig. 6 I have shown a modification of my device in which the switch-base is formed with a flange 25 for retaining the casing for the cluster in position. In other respects this form of device is similar to the device 35 shown in the other figures of the drawings.

As above stated, the hole 3 in the base of the cluster is provided for the passage of the supply-wires into the interior of the casing. One of said wires is joined with the strip 40 which connects the center contacts for the lamps and the other is passed through the opening in the bottom of the truncated plate and an aperture in the base of the switch and connected with one of the stationary contacts 45 by the binding-posts, as above described. The binding-post of the other contact of said switch is connected with the truncated contact-plate by the pin which is attached to the binding-post of said contact and the truncated plate. In this arrangement of the connections of the circuit-wires the lamps will 50 be connected in circuit in multiple when the switch is closed, the circuit for the lamps being traced from the center contacts through the lamps to the truncated contact-plate, thence through the pin 20 through the switch to the other side of the circuit. Of course 55 the lamps may be cut out of circuit at any time by operating the switch. By slight 60 change in the circuit arrangement the lamps might be connected in series and the switch used to equal advantage therewith.

There are of course many changes in the 65 details of construction herein shown and described for the purpose of disclosing my in-

vention which may be made without in any way departing from the spirit of my invention.

In Letters Patent Nos. 721,774 and 721,777, dated March 3, 1903, I have shown several 70 ways of supporting the lamp-receivers and associated contacts in position within the structure formed by the supporting-base and the inclosing casing, and it will be understood that instead of employing the supporting 75 means herein illustrated I may employ the means shown in said Letters Patent aforesaid or any other suitable supporting means.

Having described my invention, what I claim as new, and desire to secure by Letters 80 Patent, is—

1. In a device of the character described, the combination with a main supporting-base, of a supplemental base suitably supported in position in front of and parallel to said main 85 base, a plurality of lamp-holding devices having associated contacts and located between said bases, and all the elements of a switch mounted upon said supplemental base for controlling the contacts of said lamp-holding 90 devices, substantially as described.

2. In a device of the character described, the combination with a main supporting-base, of an insulating supplemental base suitably supported in front of and parallel to said 95 main base, a plurality of lamp-holding devices having associated contacts and disposed between said bases, a casing for said devices having openings to permit the passage of lamp-bases into said devices and an opening 100 to accommodate said supplemental base, and all the elements of a switch mounted upon said supplemental base for controlling the contacts of said lamp-holding devices, substantially as described. 105

3. In a device of the character described, the combination with a main supporting-base, of a supplemental base of insulating material, suitable means between said bases for supporting said bases in parallel positions, a 110 plurality of lamp-holding devices carried by said means, a casing for said devices having openings to receive lamp-bases and an opening to receive said supplemental base, and the elements of a switch mounted in front of said supplemental base, said switch elements being insulated from said casing by said supplemental base, substantially as described. 115

4. In a device of the character described, the combination with a main supporting-base, 120 of a supplemental base of insulating material, a plurality of lamp-holding devices located between said bases and supporting said bases in parallel positions, a casing for said devices having openings to accommodate said lamp-holding devices and an opening for said supplemental base, screw-threaded bushings for said openings adapted to insulate said devices from said casing and to support said casing in position, switch-contacts all mounted upon 125 130

- the front of said supplemental base for controlling the contacts of said lamp-holding devices and a suitable supplemental casing for said switch-contacts, substantially as described.
5. In a device of the character described, the combination with a main supporting-base, of a supplemental base of insulating material suitably supported in a parallel position to 10 said main base and in front thereof, a plurality of lamp-holding devices located between said bases, a casing for said bases having holes to accommodate said devices and an opening for said supplemental base, an annular shoulder formed upon said supplemental base adapted to engage said casing and support said casing in position, and switch-contacts mounted upon said supplemental base, said contacts being insulated from said casing 15 by said supplemental base, substantially as described.
6. In a device of the character described, the combination with a main supporting-base, of a supplemental base of insulating material, 20 means carrying lamp-holding devices and supporting said bases in parallel positions, a pin secured to said means and extending through said supplemental base, switch-contacts mounted upon said supplemental base, and means for 25 connecting said pin with one of said switch-contacts, substantially as described.
7. In a device of the character described, the combination with a main or supporting base, of a supplemental base of insulating material, 30 means carrying lamp-holding devices and supporting said bases in parallel positions, a pin secured to said means and extending through said supplemental base, switch-contacts mounted upon said supplemental base, means for connecting said pin with one of said switch-contacts, and means for 35 connecting a supply-wire with the other switch-contact, substantially as described.
8. In a device of the character described, 40 in combination, a main supporting-base of suitable material, a supplemental base arranged in front of and parallel to said supporting-base and suitably supported in posi- 45
- tion, a plurality of lamp-holding devices having associated contacts and arranged between 50 said bases, and the elements of a switch arranged upon said supplemental base.
9. In a device of the character described in combination, a suitable main supporting-base, a supplemental base arranged in front 55 of and parallel to said supporting-base, a plurality of lamp-holding devices suitably supported between said supporting-base and said supplemental base, the elements of a switch arranged upon said supplemental base for 60 controlling the circuits of said lamps, and a suitable inclosing casing having openings to accommodate the lamp-bases and a centrally-disposed opening to accommodate the switch elements. 65
10. In a device of the character described, in combination, a main supporting-base of suitable material, a supplemental base arranged in front of and parallel to said supporting-base and suitably retained in position, 70 a plurality of lamp-holding devices having associated contacts and arranged between said supporting-base and said supplemental base, and the complete elements of a switch carried upon the front of said supplemental base and 75 adapted to control the circuits of the lamp supported by said devices.
11. In a device of the character described, in combination, a suitable main supporting-base, a supplemental base arranged in front 80 of and parallel to said supporting-base and suitably supported in position, a plurality of lamp-holding devices arranged between said bases and having associated contacts, and switch-contacts arranged upon the front of 85 said supplemental base and suitably connected with the contacts of said lamp-holding devices in the rear of said supplemental base.
- In witness whereof I have hereunto subscribed my name in the presence of two witnesses. 90
